UNITED STATES PATENT OFFICE.

JAMES ROYS MILLER, OF PITTSBURGH, PENNSYLVANIA.

APPARATUS FOR RECLAIMING OIL.

1,359,614.

Specification of Letters Patent. Patented Nov. 23, 1920.

Application filed January 15, 1919. Serial No. 271,242.

To all whom it may concern:

Be it known that I, JAMES R. MILLER, a citizen of the United States, residing at Pittsburgh, county of Allegheny, and State 5 of Pennsylvania, have invented certain new and useful Improvements in Apparatus for Reclaiming Oil, of which the following is a specification.

My invention relates to improvements in 10 apparatus for reclaiming oil, and it consists in the combinations, constructions and arrangements herein described and claimed.

An object of my invention is to provide 15 an apparatus by means of which lubricating oil, such as the oil drained from the crank cases of internal combustion engines, may be reclaimed and made fit for use.

A further object of my invention is to 20 provide an apparatus for coagulating the dirt, for driving off the volatile hydro-carbons with which the oil is contaminated, and for preventing the formation of emulsions 25 during the process without, however causing any substantial change in the composition of the reclaimed oil, thereby producing a product which is to all intents and purposes, the equivalent of new oil.

A further object of my invention is to 30 provide an apparatus by means of which the oil to be reclaimed is brought into intimate contact with a heating medium for driving off the volatile portions, such as gasolene, which has worked its way down into the 35 crank case, said apparatus having means for drawing off the reclaimed oil at various levels, so as to obviate the danger of drawing off with the reclaimed oil any sludge or dirt.

A further object of my invention is to 40 provide improved means for agitating and simultaneously heating the oil, these means consisting of a steam jet which tends to circulate the oil, and at the same time causes the spraying of the latter upon a splash plate, so as to insure the treatment of all 45 portions of the oil.

Other objects and advantages will appear in the following specification, and the novel features of the invention will be particularly pointed out in the appended claims.

My invention is illustrated in the accompanying drawings, forming part of this application, in which—

Figure 1 is a central sectional view through the oil container,

Fig. 2 is a side view of the container and

storage tank, an intermediate filter being shown in section,

Fig. 3 is a detail view of one of the heating coils,

Fig. 4 is a detail view of a plug, and 60

Fig. 5 is a sectional view of an adjustable means for drawing off oil.

In carrying out my invention, I provide a casing 1 having a steam jacket 2. The latter is provided with a steam inlet 3 which may 65 be controlled by a thermostat 4, and which is provided with a drain pipe 5 near the bottom thereof. The bottom of the casing 1 is of conical shape, as shown at 6. A drain pipe 7 is arranged to discharge from the 70 bottom and is provided with a valve 8. The top of the casing 1 is open, but it is arranged to be closed by means of a cover 9 of conical shape, having an outlet pipe 10 at its top for permitting the escape of volatile matter 75 within the casing. Handles 11 are provided for removing the cover when desired. A steam coil 12 is disposed in the bottom as shown in the drawings, this coil being provided with an inlet pipe 13 controlled by a 80 valve 14, and having an outlet pipe 15 provided with a drip valve 16.

A steam inlet pipe 17 has its inner end bent upwardly as shown at 18, being disposed in a tube or sleeve 19, this tube being 85 closed at its bottom and open at its top at a point above the normal oil level. Communicating with the tube 19 is a pipe 20, which is provided with perforations 21. Communication between the pipe 20 and the 90 tube 19 is controlled by means of the valve 22. A pipe 23 extends downwardly toward the bottom, and also communicates with the tube 19, and is controlled by means of the valve 24. Near the top of the casing 1 is a 95 plate 25 which is supported by means of a bracket 26, or in any other suitable manner, this plate serving as a splash plate, as described later, and being spaced from the walls of the casing to permit free access of 100 the volatile portion of the matter within the casing from the body of the casing to the top thereof. An operating rod 27 extends upwardly through the splash plate, and is used to manipulate the valve 22. A similar 105 rod 28 affords a means for manipulating the valve 24.

The cone shaped bottom 6 is provided with a pocket 29 through which a drain pipe 30 extends. In Fig. 5 I have shown a detailed 110

view of the upper end of the drain pipe 30. As will be seen, it is provided with a threaded bushing 31 arranged to receive a threaded pipe or nipple 32. The upper end of the 5 nipple is provided with a head 33 which has a threaded opening arranged to receive a screw plug 34, having a semi-spherical top. The plug is provided with a slot 35 arranged to engage a key or pin 36 extending through 10 the nipple. A handle 37 is provided for manipulating the plug 34.

From the foregoing description of the various parts of the device, the operation thereof may be readily understood. The 15 dirty oil is conveyed into the casing or receiver 1 by any suitable means, the top 9 being removable for this purpose. Steam is turned into the steam jacket 2, this jacket being provided with a steam gage 38. Steam 20 is also admitted into a closed steam coil 12 in the bottom of the reclaimer. The oil in the casing or receptacle is allowed to heat up to a temperature between 210° Fahrenheit and 220° Fahrenheit. When the oil 25 has reached the desired temperature, steam is admitted through the pipe 17 to the steam jet, and at this point the valve 22 is manipulated so as to cause oil to flow through the perforations 21 at various levels into the 30 pipe 20 and thence into the jet pipe 19, being drawn through these pipes by the action of the steam. The pipe 23 at this time is closed by means of the valve 24. This steam jet is allowed to operate from one to two 35 hours, or until the oil in the container has reached the desired flash point. When this flash point has been reached, the valve 17' is closed shutting off the steam, and the valve 22 is also closed. From the time that 40 the steam jet is turned on until it is turned off again, the temperature of the oil is maintained at from 210° Fahrenheit to 220° Fahrenheit. When the steam jet is turned off the oil is allowed to cool by cutting off 45 the steam to the steam jacket 2 and the closed coil 12. When the temperature of the oil has fallen below 180° Fahrenheit, a soap solution is added to the oil in the container. Any suitable animal or vegetable 50 soap may be used. I prefer to make this solution by dissolving the soap in hot water in the proportions of one pound of soap for four gallons of hot water. From one to five pounds of the soap may be used for 55 each one hundred gallons of oil to be reclaimed, the exact number of pounds of soap per one hundred gallons of oil depending upon the amount of foreign matter in the dirty or used oil.

60 After the soap solution has been added the valves 17' and 24 are now opened, and the steam jet causes a circulation of the oil and soap solution. The action of the steam is to project the liquid up against the splash 65 plate 25. In the first use of the steam jet,

i. e., before the soap solution is introduced, the hot steam coming into contact with the oil tends to vaporize any of the volatile impurities, such as gasolene, and the vapors find their way up past the splash plate and 70 out of the pipe 10. As the oil is thrown against the splash plate, it tends to break up or spread out into fine spray, thus permitting the steam to have access to all portions thereof, so that the volatile matter is quickly 75 vaporized. When the soap solution is added, the same effect is obtained, that is to say it brings the solution into contact with all the portions of the oil through the agitation of the latter, and more especially because of the projection of the soap solution and oil against the splash plate. The soap solution tends to coagulate the dirt and other foreign matter in the oil, and this coagulated dirt gravitates toward the bot- 80 85 tom.

When the coagulation of the dirt is complete, the valves 17' and 24 are closed, and steam is again admitted into the jacket 2 and the coil 12, and the temperature of the 90 oil in the reclaimer is raised to 210° Fahrenheit to 220° Fahrenheit, and maintained until all the moisture present in the oil is driven off. When the oil is moisture free, the steam to the closed coil 12 is shut off, and the thermostat 4 is regulated to maintain the temperature of the oil at 160° Fahrenheit to 180° Fahrenheit until the coagulated 95 dirt and foreign matter has settled to the bottom of the reclaimer.

100 For the purpose of drawing off the re-claimed oil, I provide a series of cocks arranged at different levels around the casing 1, these cocks discharging into a trough 40 discharging in turn by means of a pipe 41 into an oil filter 42. The latter is composed preferably of a filter cloth disposed on the interior of a wire screen, and effectually removes any foreign matter that might have been carried over. The oil from the filter 105 passes into the main storage tank 45.

In drawing off the oil, the cocks 39 are tested successively from the bottom upward, until one is found discharging oil with no sludge, when it, or those above it, are used 110 to draw off the pure oil.

In order to permit the oil to be drawn off below the cocks 39 at varying height, I provide the oil draining apparatus already described. Normally the screw plug 34 fills 120 the top of the nipple 32. The surfaces of the plug 34 and the head 33 are rounded so as to prevent accumulation of sludge on the top thereof. Now when it is desired to drain oil below the cocks 39, the screw plug 125 34 is screwed until it is free of the head 33. It is then lowered and turned until the slot 35 engages the key 36, when the nipple 32 may be screwed into or out of the pipe 30, thus decreasing or increasing its effective 130

length so that the oil may be drained from any level within the effective reach of the nipple. In order to close the nipple it is only necessary to draw up the screw plug 5 and turn it until the opening has been closed.

Among the advantages secured by the process and apparatus as set forth above is the fact that the oil, although agitated, is 10 kept from forming an emulsion with the water by the heat, while at the same time the heat is not sufficient to cause the breaking up or the disintegration of the oil itself. The coagulated mass which forms in the 15 bottom of the receiver, may be drawn off from time to time by opening the drain pipe at the bottom of the receiver.

I claim:

1. In an apparatus for reclaiming oil, a 20 receptacle having a steam jacket and being provided with an outlet at the top, a horizontally disposed splash plate carried by the walls of the receptacle above the normal level of the oil in the receptacle, a steam 25 injector disposed within the receptacle in the bottom thereof and having a nozzle directed toward the splash plate, a branch pipe connecting with the steam injector for entraining oil at different levels, an adjustable 30 means within the receptacle for drawing the oil off to any predetermined level, said last named means comprising an outlet pipe, a threaded sleeve forming an extension for said outlet pipe, and having an 35 opening at its top, a threaded closure for said opening arranged to enter said sleeve to clear the opening, and means carried by said sleeve and arranged to be engaged by 40 said threaded closure for operating said sleeve.

2. In an apparatus for reclaiming oil, a receptacle, a steam injector disposed within the receptacle, means communicating with the steam injector for entraining oil at different levels, additional means for entrain- 45

ing the contents of the receptacle near the bottom thereof, said additional means also communicating with said steam injector, and means for controlling either of said entraining means at will. 50

3. In an apparatus for reclaiming oil, a receptacle, a steam injector disposed within the receptacle, means communicating with the steam injector for entraining oil at different levels, additional means for entraining 55 the contents of the receptacle near the bottom thereof, said additional means also communicating with said steam injector, means for controlling either of said entraining means at will, and means for heat- 60 ing the receptacle.

4. In an apparatus for reclaiming oil, a receptacle, a steam injector disposed within the receptacle, means communicating with the steam injector for entraining oil at different levels, additional means for entraining 65 the contents of the receptacle near the bottom thereof, said additional means also communicating with said steam injector, and adjustable means within the receptacle for 70 drawing off oil down to any predetermined level.

5. In an apparatus for reclaiming oil, a receptacle, a steam injector disposed within the receptacle, means communicating with 75 the steam injector for entraining oil at different levels, additional means for entraining the contents of the receptacle near the bottom thereof, said additional means also communicating with said steam injector, 80 and adjustable means within the receptacle for drawing off oil down to any predetermined level, said last named means comprising an outlet pipe, an adjustable extension for said outlet pipe, and having an 85 opening at its top, and a closure for said opening adapted to operate the adjustable extension.

JAMES ROYS MILLER.
